UNITED STATES PATENT OFFICE.

EDWARD T. MERRITT, OF CAPEVILLE, VIRGINIA, ASSIGNOR OF ONE-HALF TO FRANK PARSONS, JR., OF CAPEVILLE, VIRGINIA.

BELT-GEARING.

1,169,854.

Specification of Letters Patent.

Patented Feb. 1, 1916.

Application filed February 12, 1915. Serial No. 7,751.

To all whom it may concern:

Be it known that I, EDWARD T. MERRITT, a citizen of the United States, residing at Capeville, in the county of Northampton and State of Virginia, have invented new and useful Improvements in Belt-Gearing, of which the following is a specification.

This invention relates to an improved belt gearing particularly adapted to carriage feed mechanism for stave sawing machines, or the like, wherein a relatively quick and short reciprocating movement is given the carriage, and has for an object to provide a mechanism to take the place of the hand and which has the same flexibility and range of adjustment that is had by manually operating the carriage.

Another object of the invention is to provide a feed mechanism of this character which is relatively simple in construction, which is yieldable in operation with a great range of adjustment and flexibility, which is controlled by a single operating handle so arranged as to insure the safe operation of the machine with no danger of injury to the operator, which may be immediately stopped at any point of operation, which is provided with means for automatically returning the carriage to loading position out of the path of the saw, which may be attached to any type of machine having a movable part adapted to be reciprocated, which may be coupled with a line shaft and which while adjustable does not necessitate the stopping of the line shaft or the disconnection of the feeder therewith, and which materially increases the output of the saw or other machine to which it is applied.

The above and other objects and advantages of this invention will be more clearly brought out in the following detail description of the present embodiment of this invention, the same being shown in the accompanying drawings wherein—

Figure 1 is a side elevation of the improved feeder as applied to a stave sawing machine. Fig. 2 is a top plan view of the same. Fig. 3 is a longitudinal central section through the improved feeder. Fig. 4 is an inner end view of the same. Fig. 5 is an outer end view of the feeder.

Referring to these drawings, wherein like parts are designated by similar characters of reference throughout the several views, and particularly to Figs. 1 and 2, it will be seen that the improved feeder is applied to a stave sawing machine, the latter having a frame or runway 10 over which is mounted a tubular saw 11, and mounted to reciprocate upon the runway or frame 10 is a carriage 12. As may be seen from Fig. 2 the carriage 12 moves against one side of the saw in the usual manner, and is provided with suitable means for supporting a block or bolt of wood 13 adapted to be cut into staves.

The feeder of this invention is shown in the present instance as comprising a substantially rectangular frame 14 in the top of which is journaled a transverse shaft 15, the latter being located intermediate the ends of the frame 14. The outer end of the shaft 15 carries a crank arm 16 or the equivalent thereof, to which is connected one end of a pitman 17. The opposite end of the pitman has pivotal connection, as at 18, with the carriage 12 of the saw.

The shaft 15 is also provided with a fixed driving pulley 19, of any approved design, and having in one side a counterweight 20 arranged substantially at 90° from the crank arm 16 toward the outer end of the feeder, as shown in Fig. 1, whereby when the driving pulley 19 is released the counterweight 20 turns the shaft 15 to normal position and holds the carriage 12 out of engagement with the saw, or in loading position.

In one end of the frame, the outer end being shown in the present instance, there is a transverse drive shaft 21 having on one end, beyond the frame 14, a pulley 22 adapted to receive a belt from a line shaft, or other suitable source of power to drive the shaft 21. Hinged upon the shaft 21, and in spaced relation to one another, is a pair of link bars 23, in the outer ends of which is journaled a transverse shaft 24 arranged in parallelism with the drive shaft 21. The drive shaft 21 has fixed thereon a pulley 25 located between the link bars 23 and in line with an idler pulley 26 mounted upon the shaft 24. A belt 27 passes over the pulleys

25 and 26 and is adapted to be continuously driven by the drive shaft 21 immediately beneath and in alignment with the drive pulley 19 on the main shaft 15. The 5 opposite ends of the idler shaft 24 project laterally beyond the link bars 23 and are adapted to normally rest upon supports 28 arranged in the opposite sides of the frame 14. In this manner the swinging end of 10 the belt 27 is normally supported in the frame 14 out of contact with the drive pulley 19.

The free ends of the link bars 23, as may 15 be best seen from Figs. 4 and 5, are joined by a cross-piece 29 having a rod 30 hinged thereto, the rod extending upwardly therefrom in the frame 14 and being pivoted at its upper end to an operating handle 31. The handle 31 is hinged intermediate its 20 ends upon an arm 32 rising from the frame 14, the handle 31 extending substantially horizontally and laterally from the frame 14 to a position above the pitman 17 and removed from the operating parts of the 25 device.

In use the frame is secured in any suitable manner against the end of the saw frame 10. The pitman 17 is connected to the carriage 12 of the saw, and the pulley 30 22 is connected to any suitable source of power for turning the drive shaft 21. The shaft 21 is adapted to be continuously operated so as to keep the belt 27 constantly in motion at the desired speed.

35 The counter-weight 20 normally rests at the bottom of the drive pulley 19 and thus holds the saw carriage in retracted or loading position. When it is desired to operate the carriage all that is necessary to do is to 40 gradually draw down the the outer end of the hand lever 31. This gradual movement raises the free end of the belt 27 and brings the top of the belt into gradual contact with the bottom of the drive pulley 19. The 45 drive pulley 19 is thus gradually started and as the lever 31 is further depressed and the belt 27 is tightened against the drive pulley 19, the pulley 19 takes up the speed of the belt and reciprocates the carriage. 50 Should it become necessary to suddenly stop the carriage the handle 31 is released whereupon the belt 27 immediately drops out of engagement with the drive pulley 19 and the counterweight 20 returns the carriage 12 55 to its normal retracted position. It is thus seen that should the bolt or block of wood jam or be misplaced, or any accident happen to the saw proper and its parts, the feeder may be instantly stopped and the 60 carriage be automatically withdrawn out of contact with the saw.

All of this operation is effected by the hereinabove described device which is of very simple construction, may be econom-

ically installed, may be operated by un- 65 skilled labor, materially increases the output of the saw machines as at present operated, and provides for a machine which possesses not only all of the advantages above enumerated but which is capable of the same 70 flexibility and adjustment in its operation as is had by operating the carriage manually, the latter being the only present successful method found.

It is of course understood that various 75 changes in the detail construction and design of the above described embodiment of this invention may be made within the scope of the following claims without departing from the spirit of this invention. 80

What is claimed is—

1. In a device as specified, an upright frame, a driven shaft journaled transversely in the top of the frame, a friction pulley on the driven shaft, a drive shaft mounted 85 in one end of the frame adjacent the lower part thereof and adapted to be continuously driven, a pulley on the drive shaft, a pair of arms hinged to the drive shaft at the opposite sides of the pulley thereon and extending longitudinally within the frame, a shaft journaled between the outer ends of the arms, a pulley mounted on said last-named shaft, a belt arranged over the pulley of the drive shaft and the pulley at the 95 outer ends of the arms, a bracket rising from the top of the frame at one end thereof, a hand lever pivoted in the bracket and extending laterally from the frame, and a connection between the inner end of the 100 hand lever and the free ends of said arms whereby said belt may be raised against the pulley on said driven shaft and yieldingly held there by hand pressure.

2. In a device as specified, a main frame, 105 a driven shaft in the frame, a pulley on said shaft, a frame pivoted at one end to the main frame and adapted for free vertical movement at the other end, a longitudinally extending belt mounted in said pivoted frame below said pulley, a hand-lever extending transversely over the main frame and projecting beyond the same, and a connection between the inner end of the hand-lever and the free end of the pivoted frame 110 to raise the belt against the pulley by hand pressure, said pivoted frame and belt instantaneously and automatically moving away from said pulley when pressure upon the lever is relieved. 115

3. In a device as specified, a main frame, a driven shaft in the frame, a pulley on said shaft, a frame pivoted at one end to the main frame and adapted for free vertical movement at the other, a belt arranged longitudinally in the pivoted frame, a rest in the lower end of the first mentioned frame 125 adapted to normally support the free end

of the pivoted frame, and a hand-lever projecting from the upper end of the main frame and having connection with said free end of the pivoted frame whereby to raise
5 the belt against the pulley and yieldingly hold the pulley and the belt in contact.

In testimony whereof I have hereunto set

my hand in presence of two subscribing witnesses.

EDWARD T. MERRITT.
